[57] **CLAIM**

The ornamental design for a two-piece operator head for a tool-operated lock, as shown and described.

DESCRIPTION

FIG. 1 is a perspective view of a two-piece operator head for a tool-operated lock showing my new design; FIG. 2 is a top plan view thereof; FIG. 3 is an elevational view of either of the right or left sides thereof; FIG. 4 is an elevational view of either of the front or rear sides thereof; and, FIG. 5 is a sectional view thereof as seen from a plane indicated by a line 5—5 in FIG. 3. The broken lines representing the operating shaft is shown for illustrative purposes only.
